Filed Oct. 23, 1967, Ser. No. 9,108

Term of patent 14 years

(Cl. D45—16)

FIG. 1

FIG. 2

FIG. 3

FIG. 1 is a top plan view of a necklace or similar article showing my new design; some of the beads being in a pivoted position;

FIG. 2 is a perspective view, on an enlarged scale, of one of the beads per se that forms a part of my design; and

FIG. 3 is an end view, on an enlarged scale, of the bead per se.

The dominant features of my design reside in the full-line portions of the drawing.

I claim:

The ornamental design for a necklace or similar article, substantially as shown and described.
